UNITED STATES PATENT OFFICE.

ERNEST W. FREDRICKSON, OF KINBRAE, MINNESOTA.

ATTACHMENT FOR DOOR-LOCK ESCUTCHEONS.

Application filed April 10, 1923, Serial No. 631,155. Renewed June 2, 1924.

To all whom it may concern:

Be it known that I, ERNEST W. FREDRICKSON, a citizen of the United States, residing at Kinbrae, in the county of Nobles and State of Minnesota, have invented certain new and useful Improvements in Attachments for Door-Lock Escutcheons, of which the following is a specification.

The present invention relates to an attachment for a door lock escutcheon and has for its principal object to provide means for preventing the removal of the key to the door lock when desired.

Another important object of the invention is to provide a device of this nature which may be readily placed upon the ordinary escutcheon without much trouble.

A still further object of the invention is to provide a device of this nature which will be simple and efficient in construction, reliable, durable, inexpensive to manufacture, and well adapted to the purpose for which it is designed.

With the above and numerous other objects in view as will appear as the description progresses, the invention resides in certain novel features of construction, and in the combination and arrangement of parts as will be hereinafter more fully described and claimed.

In the drawing

Figure 1 is a front elevation of an escutcheon showing my invention applied thereto.

Figure 2 is a rear elevation thereof.

Figure 3 is a detail section taken therethrough, and

Figure 4 is a perspective view of the elements forming the attachment showing the same disassembled.

Referring to the drawing in detail it will be seen that an ordinary escutcheon or guard plate is shown at 1 being provided with the usual key hole 2 and a transversely extending slot 3 therein disposed above the key hole 2. A headed pin 4 pierces the slot 3 so as to be movable therein and supports the elements of the attachment.

The attachment includes a plate 5 which is preferably of sheet metal and square in formation. This plate 5 is constructed with an aperture 6 for receiving the pin 4 and with a keyhole 7 having a slot 8 projecting transversely therefrom and communicating therewith. A guide bar 9 is attached to the

rear face of the escutcheon 1 above the slot 3 and is preferably secured by solder or the like. The upper edge of the plate 5 is adapted to abut the under edge of this guide bar 9 thus preventing any tendency of the plate 5 to rotate when the pin 4 is moved in the slot 3 and it will be seen that the plate 5 will move with the pin so that the key hole 7 will come in and out of registry with the key hole 2. In order to strengthen the attachment and aid the efficiency of operation thereof a brace plate or washer 10 is provided with a central aperture 11 for receiving the pin 4 and is disposed to rest on the rear face of the plate 5 and on the bar 9 as is illustrated to advantage in Figure 2. This plate 10 is formed of suitable spring material and has a certain braking effect upon the attachment which is accomplished by constructing the bar 9 with a slightly greater thickness than the plate 5 so that the plate 10 will slightly bind upon the bar 9 tending to resist movement of the pin 4 and plate 5 so that when the plate is moved to a desired position it will not be possible for an unauthorized person to move the same. This is especially desirable in that the plate 5 is prevented from moving when the door is slammed.

When the attachment is positioned as disclosed in Figure 2, it being understood that the escutcheon shown is on the inside of the door, the key may readily be inserted into the lock. When the key is inserted and it is desired to retain the key in the door lock so that a key cannot be inserted from the exterior, the plate 5 is moved through the intermediacy of the pin 4. When in this dotted line position the shank of the key will project through the slot 8 but cannot be removed from the lock as is evident.

I have, in the present instance, shown and described the preferred embodiment of the device which will give in practice satisfactory and reliable results, and it is to be understood that the same is susceptible of modification in various particulars without departing from the spirit or scope of the invention as defined in the claim or sacrificing any of its advantages.

Having thus described my invention, what I claim as new is:

In combination, an escutcheon including a key hole, a slot, a pin projected through

the slot, a plate mounted on the pin and provided with a key hole and a slot projecting therefrom, said pin being movable to actuate the plate so that its key hole may be placed in and out of registry with the key hole of the escutcheon, a resilient plate carried by the pin, a guide bar fastened to the escutcheon, said resilient plate adapted to bear on said bar so as to brake the move-

ment of the first mentioned plate whereby 10 accidental movement thereof will be prevented.

In testimony whereof I affix my signature in presence of two witnesses.

ERNEST W. FREDRICKSON.
